UNITED STATES PATENT OFFICE.

ARTHUR E. HOURD, OF LONDON, CANADA.

DESIGN FOR A GAME-BOARD.

SPECIFICATION forming part of Design No. 30,396, dated March 28, 1899.

Application filed February 23, 1898. Serial No. 671,387. Term of patent 14 years.

To all whom it may concern:

Be it known that I, ARTHUR E. HOURD; a subject of Her Majesty the Queen of Great Britain, and a resident of London, in the 5 Province of Ontario and Dominion of Canada, have invented and produced a certain new and original Design or Useful Shape for Game-Boards, of which the following, in connection with the accompanying drawings, is a full, 10 clear, and exact specification.

In the said drawings, Figure 1 is a top or plan view of a game-board embodying my design, and Fig. 2 is a transverse sectional view thereof.

15 The leading features of my design consist of a round board A and its outer rim or border-wall B, which is also round or circular, the annular ditch or countersink a, of which the rim B forms the outer wall, and the central flat board A, whose outer edge forms the 20 inner wall of the ditch a.

The board A is substantially flat, excepting for a marginal or surrounding ditch or countersink a adjacent to the wall B, while at its center is formed a comparatively small 25 depression a', standing around which on the line of a circle C are a number of posts or pins D. The circle C is surrounded by a circle E and this in turn by a circle F, which is very near the edge of the ditch a. The two 30 circles E and F are conjoined on the diameters of the board by four straight lines G.

I claim—

The design for a game-board substantially as herein shown and described.

ARTHUR E. HOURD.
